United States Patent

Des. 236,568
Patented Sept. 2, 1975

236,568

CABINET FOR KEYS

Brian D. Savage, 3555 Valley Circle,
Birmingham, Ala. 35243

Filed Jan. 17, 1974, Ser. No. 434,233

Term of patent 14 years

Int. Cl. D6—04

U.S. Cl. D6—127

Fig. 1

Fig. 3

Fig. 2

FIG. 1 is a front elevational view of a cabinet for keys showing my new design in the open position, the sides and back being plain and unornamented, the keys and holders being shown in broken lines for illustrative purposes only;

FIG. 2 is a top plan view thereof; and

FIG. 3 is a front elevational view thereof in the closed position.

I claim:

The ornamental design for a cabinet for keys, as shown and described.
